United States Patent Office

Des. 212,533
Patented Oct. 29, 1968

212,533

WHEEL AND TIRE COMBINATION

Irwin R. Barr, Lutherville, Md., assignor to AAI Corporation, Cockeysville, Md., a corporation of Maryland
Filed May 3, 1967, Ser. No. 6,938

Term of patent 14 years

(Cl. D14—30)

Fig. 1

Fig. 2

Fig. 3

FIG. 1 is a perspective view of the wheel and tire combination,

FIG. 2 is an outer end elevational view of the wheel and tire combination of FIG. 1,

FIG. 3 is an inner end elevational view of the wheel and tire combination of FIG. 1.

The dominant features of my design reside in the portions shown in full lines.

I claim:

The ornamental design for a wheel and tire combination, as shown.
